United States Patent Office

Des. 219,852
Patented Feb. 2, 1971

219,852

MICROWAVE OVEN

Alan W. Duncan, Itasca, and John L. Berman, Hickory Hills, Ill., assignors to Roper Corporation, Kankakee, Ill.

Filed Sept. 17, 1969, Ser. No. 19,195

Term of patent 14 years

Int. Cl. D7—04

U.S. Cl. D81—4

FIG. 1 is a perspective front view of a microwave oven showing our new design;

FIG. 2 is a perspective back view of the same device;

FIG. 3 is a fragmentary section looking along the line 3—3 in FIG. 1; and

FIG. 4 is a fragmentary section looking along the line 4—4 in FIG. 1.

We claim:

The ornamental design for a microwave oven, substantially as shown.
